UNITED STATES PATENT OFFICE.

FRED PACKARD, OF BROCKTON, MASSACHUSETTS.

BOOT OR SHOE.

SPECIFICATION forming part of Letters Patent No. 297,156, dated April 22, 1884.

Application filed February 18, 1884. (No model.)

To all whom it may concern:

Be it known that I, FRED PACKARD, of Brockton, county of Plymouth, State of Massachusetts, have invented an Improvement in 5 Boots or Shoes, of which the following description, in connection with the accompanying drawings, is a specification, like letters on the drawings representing like parts.

This invention has for its object to strengthen 10 the edge of a button-hole piece of a button boot or shoe, and prevent the button-hole slits from being torn out or through the outer edge of the button-hole piece, and at the same time provide the same with a better-appearing edge.

15 In accordance with my invention I place within the turned-over or folded outer edge of the button-hole piece a piece of strong cord or other flexible stay-strip, and secure the same therein by a line of stitches, the said stitches 20 being made between the said cord or stay-piece and the large ends of the said button-holes. I have also provided the turned-over edge of the upper edge of the top part or quarter of the shoe with a strong cord or stay-piece, to obviate 25 the employment of piping as now commonly used.

Figure 1, in side elevation, represents a button-gaiter embodying my invention, a portion of the button-hole piece and of the vamp being 30 broken out to clearly illustrate the cord or stay-piece. Fig. 2 is an enlarged inner side view of the button-hole piece, with most of its lining omitted. Fig. 3 is a partial section of Fig. 2 in the dotted line x , and Fig. 4 is a partial section on the dotted line $x^2 x^2$.

35 The vamp a and sole b may be of any usual shape or material.

The top part, c , of the shoe, of usual material and shape, has an attached button-hole piece, d , usually cut from leather and provided 40 with button-holes e .

45 Referring to Fig. 2, it will be seen that the outer edge of the button-hole piece d is turned over or folded upon itself, as at d^2 , and in the said fold I have laid a strong cord or stay-piece, f , which in practice I prefer to make of linen or flax; but it may be of any other strong material, or of wire.

To enable the edge of the button-hole piece 50 to be folded over the said cord and be laid smoothly, I prefer to first cut or snip the edge

of the button-hole piece for a short distance, as best shown in Fig. 2. The end 3 of the cord (see Fig. 2) may, and will preferably, in the completed shoe, be extended about the entire 55 top of the shoe within the turned-over upper end of the same, as in Fig. 1, where the top part is shown as broken out. The end 4 of the said cord or stay-piece will be extended down between the vamp and its lining a^2 , (see 60 Fig. 1,) where the vamp is broken out, and it will rest there while the usual seams g , uniting the vamp with the lower end of the button-hole piece and top part, are being made, the said seams crossing over the said cord or 65 stay-piece. The lining h of the button-hole piece is stitched to it between the folded corded edge of the button-hole piece and the outer ends of the button-holes by one or more lines of stitches, as at m , one row of stitches being 70 also made along the said cord and about the said button-holes.

The cord or stay-piece laid within the turned-over edge adds greatly to the durability of the button-hole piece, and effectually prevents the 75 button-holes from being torn out through the edge of the button-hole piece by any strain which will ever be exerted thereon by a button-hook or by wear; and by extending the cord about the top part of the shoe within its 80 turned-over edge (see Fig. 4) a piping is rendered unnecessary and a very complete finish is obtained.

I am aware that a cord has been laid between the button-piece and the lining, but not with 85 in the overturned edge of the button-piece.

I am aware, also, that a cord has been laid about the button-hole slits, and has also been extended between the outer ends of the said slits and the row of stitching uniting the main 90 part of the button-piece with its lining. The snipped edge enables the corners to be readily turned and without forming wrinkles.

By fastening the cord f between the vamp and its lining at the junction of the button-hole piece with the vamp a very firm connection is made, which effectually prevents the tearing of the shoe at the junction of the vamp and top piece, and stays made by taking several stitches through and then over the edge 100 of the button-hole piece next the vamp are rendered unnecessary.

I claim—

1. In a button-gaiter, a button-piece having its outer edge turned over and provided with a cord or stay-piece; the same being interposed between the folded edge of the button-piece and the outer ends of the button-holes, substantially as shown, and for the purpose described.
2. A boot or shoe having a turned-over, snipped or notched and corded edge, where-by the said edge may be turned to form corners without wrinkles, substantially as described.
3. In a boot or shoe, a top piece and a but-

ton-hole piece provided with a cord or stay-piece, combined with a vamp stitched to the 15 said top piece and button-hole piece, the end of the cord or stay-piece being crossed by the stitches uniting the said parts, substantially as described.

In testimony whereof I have signed my name 20 to this specification in the presence of two subscribing witnesses.

FRED PACKARD.
